UNITED STATES PATENT OFFICE

154,242

DESIGN FOR A GARMENT HANGER

Walton B. Crane, Beverly Hills, and Morris Treiman, Los Angeles, Calif., assignors to Allied Plastics Company, Los Angeles, Calif., a corporation of California

Application September 8, 1947, Serial No. 141,247

Term of patent 3½ years

(Cl. D80—8)

To all whom it may concern:

Be it known that we, Walton B. Crane and Morris Treiman, citizens of the United States of America, residing in the cities of Beverly Hills and Los Angeles, respectively, in the county of Los Angeles, State of California, have invented a new, original, and ornamental Design for a Garment Hanger, of which the following is a specification, reference being had to the accompanying drawing, forming a part thereof.

Figure 1 is a top plan view of a garment hanger, showing my new design;

Figure 2 is a front elevation thereof;

Figure 3 is an end elevation thereof;

Figure 4 is a rear elevation thereof;

Figure 5 is a detail section taken on line 5—5 of Figure 2; and

Figure 6 is a section taken on line 6—6 of Figure 2.

The essential features of the design reside in the portions shown in full lines.

I claim:

The ornamental design for a garment hanger, substantially as shown and described.

WALTON B. CRANE.
MORRIS TREIMAN.
